[57] CLAIM

The ornamental design for a telephone, as shown and
described.

DESCRIPTION

FIG. 1 is a partial left side, partial front and top perspective view of a telephone showing our new design;

FIG. 2 is a similar perspective view with the handset inverted and spaced apart from the stand;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and

FIG. 8 is a left side elevational view thereof.

FIG. 1

FIG. 2

FIG. 3

FIG. 4

FIG. 5

FIG. 6

FIG. 7

FIG. 8
